(57) **CLAIM**

The ornamental design for a tracking array, as shown and described.

DESCRIPTION

FIG. 1 is a top perspective view of a design of a tracking array;

FIG. 2 is a bottom perspective view of the tracking array of FIG. 1;

FIG. 3 is a top view of the tracking array of FIG. 1;

FIG. 4 is a bottom view of the tracking array of FIG. 1;

FIG. 5 is a rear view of the tracking array of FIG. 1;

FIG. 6 is a front view of the tracking array of FIG. 1;

FIG. 7 is a right-side view of the tracking array of FIG. 1; and,

FIG. 8 is a left-side view of the tracking array of FIG. 1.

Any features shown in broken lines depict environmental subject matter only and form no part of the claimed design. The navigational tracking arrays claimed herein are not limited to the scale illustrated herein and the design is applicable, for example, to robotic surgical apparatuses used to assist in surgical procedures.
